CASING FOR A HAND MANIPULABLE TRANSDUCER

Robert E. Burridge, Montclair, N.J., assignor to Litton Business Systems, Inc., Orange, N.J.

Original design application Oct. 28, 1969, Ser. No. 19,774, now Patent No. 224,541. Divided and this application Jan. 25, 1971, Ser. No. 109,726

Term of patent 14 years

Int. Cl. D14—99

U.S. Cl. D26—14 B

FIG. 1

FIG. 2

FIG. 3

FIG. 4

FIG. 5

FIG. 6

FIG. 7

FIG. 8

FIG. 9

FIG. 10

FIG. 1 is a side perspective view of a casing for a hand manipulable transducer, or similar article;

FIG. 2 is a side elevational view thereof;

FIG. 3 is a rear elevational view thereof;

FIG. 4 is a bottom plan view thereof;

FIG. 5 is a top plan view thereof;

FIG. 6 is a side perspective view of another embodiment of a casing for a hand manipulable transducer or similar article;

FIG. 7 is a side elevational view;

FIG. 8 is a rear elevational view;

FIG. 9 is a bottom plan view;

FIG. 10 is a top plan view.

This is a divisional application of design application Ser. No. D. 19,774, filed Oct. 28, 1969, now Pat. No. D. 224,541.

I claim:

The ornamental design for a casing for a hand manipulable transducer, as shown and described.
